UNITED STATES PATENT OFFICE.

HERMAN FRASCH, OF NEW YORK, N. Y., ASSIGNOR TO THE FRASCH SULPHUR PROCESS COMPANY, A CORPORATION OF MAINE.

VALVE FOR PIPES WHICH CONVEY MELTED SULFUR.

988,994.

Specification of Letters Patent. Patented Apr. 11, 1911.

Application filed October 30, 1903. Serial No. 179,231.

To all whom it may concern:

Be it known that I, HERMAN FRASCH, a citizen of the United States, residing in the city of New York, borough of Manhattan, and county of New York, in the State of New York, have invented new and useful Improvements in Valves for Pipes which Convey Melted Sulfur, of which the following is a specification.

10 This invention relates more particularly to valves for pipes which convey melted sulfur, as, for example, sulfur which has been melted artificially in an underground deposit and then forced or pumped up. See 15 my prior Patents 461,429 and 461,430, dated October 20, 1891. Each of the improvements constituting said invention is intended to be secured for all the uses to which it may, with or without modification, be 20 adapted.

Sulfur being a material which is solid at ordinary temperatures, when a pipe conveying it in a melted state is closed by a valve, the latter is liable to be stuck fast by solidifying sulfur, especially when it is in the open position; so that, when attempt is made to change the valve, it is found impossible to move it.

In accordance with the present invention, 30 the valve has a loose connection with the screw, or other part of the valve-moving means, and also has a valve stem or other projection beyond the casing adapted to be struck with a hammer or other instrument. 35 The loose connection permits the valve to move independently of the screw, and thus to be loosened from the solidified sulfur by the blow of the hammer.

Another difficulty in using valves of the 40 construction commonly employed for water to close a pipe for conveying melted sulfur arises from the liability to leak of the stuffing box through which the valve stem moves. Melted sulfur soon corrodes packing and it is besides very penetrating. Its 45 temperature is considerably above the boiling point of water; and the contact of melted sulfur with a man's skin is apt to make a bad burn; as well because of its cor-

roding action as from its high temperature; 50 so that the escape of a small quantity may be the cause of suffering and of a loss which is far beyond the value of the escaping sulfur, if the ordinary valves should be used on sulfur-conveying pipes.

55

In accordance with the present invention, the difficulty is in part overcome by arranging the handle, or equivalent device, for manipulating the valve opposite a solid part of the valve and providing connections for 60 transmitting the power therefrom to the valve stem which is located with the hole wherein it moves at a safe distance. Escaping sulfur is, therefore, not apt to reach the workman who is manipulating the valve.

65

A further feature of the invention consists in making the valve double acting with a principal seat for the pipe and a secondary seat for the hole through which the valve stem works. Thus, when the valve is fully 70 open, it stops communication between the valve chamber and the hole for the valve stem.

The invention also comprises the parts, improvements and combinations hereinafter 75 set forth.

In the accompanying drawings, which form part of this specification: Figure 1 is a side view of the new or improved valve in what is considered its most advantageous 80 form, with a sulfur-conveying pipe attached; Fig. 2 is a sectional view of the same in a plane parallel to that of Fig. 1, without the pipe; Fig. 3 is a view thereof in horizontal section; Fig. 4 is a side view 85 of another form of the valve, with attached pipe, which form is within the invention, but is considered less advantageous than the valve of Figs. 1-3, in that it lacks the arrangement by which the manipulating handle is removed away from the hole for the valve stem; Fig. 5 is a view of this latter form of valve in section in a plane parallel with that of Fig. 4; and Fig. 6 is a sectional view of the same in a vertical plane at right 90 angles to those of Figs. 4 and 5.

The casing *a*, as shown, is cast with the principal valve seat *b* at one end of the valve

chamber and has the other end of said chamber closed by a plug *c*, which is perforated with a hole for the valve stem and on which is formed the secondary valve seat *d*. The 5 valve *e* is double acting. When closed, it bears on the seat *b* and closes the communication between inlet passage *f* and outlet passage *g*, with which the two portions of sulfur pipe *h* connect, respectively. When 10 open, the valve bears upon the seat *d* and closes communication between the valve chamber and the hole through which the valve stem *k* passes. Thus there is no need for a stuffing box for the valve stem; since 15 the valve itself prevents leakage when it is full opened, which is practically about the only time the valve would hold melted sulfur; as the forcing of it from the mine would ordinarily be stopped before changing the 20 valve.

To insure against possible leakage burning the workman who may be manipulating the valve, the handle or manipulating device 25 *l* is (in the valve of Figs. 1-3) placed opposite an imperforate part of the valve casing at a suitable distance from the hole for the valve stem. For moving this valve, use is made, as shown, of a screw *m*, which is provided with a traveling nut (formed, as 30 shown, by a threaded opening in a cross piece *n*) and has its said nut connected by a bridle with the valve stem *k*, said bridle consisting of the side rods *p* sliding in ears *q* on the valve casing and the cross piece *r* fitting 35 between stops *s* on the valve stem *k*.

The screw *m* is connected with the valve casing by a head fitting in a socket, so that the screw can be turned in either direction, but cannot be moved endwise. The head and 40 socket can be made in any desired way; as shown, half of the socket is cast in with the valve casing and the other half is bolted on. The stops *s* may be formed in any suitable 45 way. As shown, both of them are integral with the valve stem, and the cross piece is notched to receive the valve stem.

In order that the valve may be loosened, should it become fast by the solidification of sulfur thereon, there is a butting or loose 50 connection between the valve and the screw for moving it. This loose connection for moving the valve to close the pipe may be made in various ways; but, as shown, it is formed by making the distance between the 55 stops *s* greater than the thickness of the intervening cross piece *r*; so that when the latter is moved inward and strikes the inner stop, without moving the valve, the outer stop *s* does not prevent the motion of the 60 valve when the workman hits the outer end of the valve stem *k* with a hammer.

It is considered best to have the stops normally and, indeed, permanently separated;

but a butting or loose connection could be made by stops which normally allowed no play to the interposed device, but which could be separated on occasion. Thus the nuts *t* on the side rods *p* could be loosened to allow of the cross piece *r* to be moved in either direction independently of the screw 65 *m*. Without loosening the nuts *t*, a tool could also be placed behind the inner one of the stops *s* for loosening the valve when it is closed and the cross piece *r* is against the outer stop *s*, said stops being separated 70 75 as shown.

As shown in Figs. 4-6, the screw *u*, carrying the handle *l*, is in the form of a sleeve, loose on the valve stem *k* between the stops *v*, which are separated by a greater distance 80 than the length of said sleeve. When the sleeve makes contact with the inner stop, the valve can be forced inward by the blow of a hammer; and when it is against the outer stop, the valve can be forced outward independently of the screw. 85

The screw sleeve engages a stationary nut (formed, as shown, by a threaded opening in the cross piece *w*), whose ends are supported by standards *x*, bolted at the foot to the valve casing and connected by collars and nuts with the cross piece *w*. By separating the collar and nut of each standard *x*, a loose connection could be established between the valve and the standards *x* independently of the space between the stops *v* being greater than the length of sleeve *u*. Standards *x* are part of the valve-moving 90 means, since they hold the principal nut *w*, which causes the screw *u* to move endwise 95 100 and so to impart motion to the valve.

I claim as my invention or discovery:

1. A valve provided with a projection beyond the valve casing and also with exteriorly located valve moving means for forcing the valve to and from its seat, said projection being arranged for receiving a blow independent of said means and having with the latter a loose valve closing connection so as to allow independent movement to the open valve in the direction of closure under a blow on said projection, substantially as described. 110

2. A valve having the five following features, namely: a projection beyond the casing adapted to be struck in order to loosen the valve by a blow, a nut outside said casing, a screw engaging said nut, means whereby one of the two last mentioned parts is held from rotation and one of them from 115 endwise movement, and a loose valve-moving connection outside said casing between said projection and said nut and screw, substantially as described. 120

3. A casing having a valve seat and also 125 a hole in the casing wall opposite said valve

seat on the valve side of said valve seat, and also having an outlet passage leading laterally through the casing wall from the space inside on the valve side of said valve seat, in combination with the valve in said casing, a valve stem projecting through said hole, a manipulating device located opposite an imperforate part of the casing, and valve moving connections between said manipulating device and said valve stem, substantially as described.

4. A double acting valve having a plain unpacked valve stem projecting through a plain hole in the casing devoid of stuffing box, together with means outside the casing for moving the valve in both directions through said valve stem and for holding the valve closed by positive pressure, and also having a principal seat on which the valve bears when closed and a secondary seat around said hole, substantially as described.

5. A double acting valve having means for moving it in both directions with a manipulating device located opposite an imperforate part of the casing and a plain unpacked valve stem projecting through a plain hole in the casing, said valve also having a principal seat on which the valve bears when closed and a secondary seat around said hole, substantially as described.

6. A double acting valve having means for moving it in both directions located outside of said casing with a loose connection between the same and the valve and a plain unpacked valve stem projecting through a plain hole in the casing, said valve also having a principal seat on which the valve bears when closed and a secondary seat around said hole, substantially as described.

7. A valve which has a loose connection with an appropriate part of the valve-moving means and a projection beyond the valve casing adapted to be struck in order to loosen the valve by a blow, and which also has a valve-manipulating device located opposite an imperforate part of said casing, substantially as described.

8. A valve having a stem projecting through the valve casing with stops outside said casing on said stem, and a movable valve-shifting device fitting between said stops so as to form with stem a loose connection which allows the valve to be moved independently of said device, substantially as described.

9. A valve having a stem projecting through the valve casing with stops outside said casing on said stem, and a movable valve-shifting device fitting between said stops which are normally or permanently separated by a wider space than the inter-

posed portion of said device occupies, substantially as described.

10. A valve having each of the following features, namely: a casing passage on one side of the valve seat, a valve stem projecting at right angles to said passage through a hole in casing on the same side of the valve seat, a nut outside said casing, a screw engaging said nut, means whereby one of the two last mentioned parts is held from rotation and one of them from endwise movement, and a connection between said stem and the part which is allowed to move endwise, substantially as described.

11. A valve having a plain valve stem projecting at one end of the casing and laterally disposed inlet and outlet passages on opposite sides of the valve seat, and also having a device for moving the valve in both directions located at the opposite end of said casing outside the same and connected with the valve stem, substantially as described.

12. A valve having the valve stem projecting at one end of the casing and laterally disposed inlet and outlet passages on opposite sides of the valve seat and also having stops on said stem, a movable valve shifting device interposed between said stops and a valve-manipulating means located at the opposite end of said casing and connected with the valve stem through said valve-shifting device, said stops being separated normally or permanently by a wider space than the interposed portion of said device occupies, substantially as described.

13. The combination with a pipe which conveys melted material, of a valve which has a projection beyond the valve casing adapted to be struck and valve moving means and also a loose connection with said valve-moving means, so that the valve can be loosened by a blow should it stick fast, substantially as described.

14. A valve having a plain valve stem projecting at one end of the casing and laterally disposed inlet and outlet passages on opposite sides of the valve seat, and also having a screw for moving the valve in both directions located at the opposite end of said casing outside the same and connected with the valve stem, substantially as described.

15. A screw down valve devoid of stuffing box and provided with a lateral outlet and also with a manipulating device located opposite an imperforate part of the casing, substantially as described.

16. A valve having a valve proper, a valve seat between inlet and outlet passages, a projection on the opposite side of said valve proper from said seat, a valve operating screw and nut outside the valve casing, and

loose valve opening and valve closing connections outside the valve casing between said projection and one of said valve operating parts, said projection extending beyond the valve casing and being adapted to be struck in order to loosen the valve by a blow should it stick in its open position, substantially as described.

In testimony whereof I have signed my name to this specification in the presence of 10 two subscribing witnesses.
